(57) **CLAIM**

The ornamental design for a miniature ratchet tool, as shown and described.

DESCRIPTION

FIG. 1 is a perspective top, front, right end view of the miniature ratchet tool;

FIG. 2 is a perspective bottom, front, left end view thereof;

FIG. 3 is a top plan view thereof;

FIG. 4 is a bottom plan view thereof;

FIG. 5 is a rear view thereof;

FIG. 6 is a front view thereof;

FIG. 7 is a right end view thereof;

FIG. 8 is a left end view thereof;

FIG. 9 is a perspective top, front, right end view of the miniature ratchet tool with a component holding drawer in a fully open position;

FIG. 10 is a perspective bottom, front, left end view thereof; and,

FIG. 11 is a top plan view thereof.

The broken lines in FIGS. 2, 4-6, and 10 illustrate features of the miniature ratchet tool that form no part of the claim.
